UNITED STATES PATENT OFFICE.

JOHN J. BRENTANO, OF ST. PAUL, OREGON.

SHOE-HOLDING STAND.

1,392,393.

specification of Letters Patent.

Patented Oct. 4, 1921.

Application filed March 28, 1921. Serial No. 456,214.

To all whom it may concern:

Be it known that I, JOHN J. BRENTANO, a citizen of the United States, residing at St. Paul, in the county of Marion, State of Oregon, have invented certain new and useful Improvements in Shoe-Holding Stands; and I do hereby declare the following to be a full, clear, and exact description of the invention, such as will enable others skilled in the art to which it appertains to make and use the same.

This invention relates to new and useful improvements in stands and particularly to stands adapted to support shoes while being polished.

One object of the invention is to provide a stand on which a shoe can be firmly and securely clamped and held against movement, while the same is being polished, the invention being particularly adapted for use in polishing shoes which are removed from the owners' feet.

Another object is to provide a device of this character which is readily adjustable to hold shoes of any size, and which holds the shoes so that the operator can use both hands in the polishing operation.

Other objects and advantages will be apparent from the following description when taken in connection with the accompanying drawings.

In the drawings:

Figure 1 is a side elevation of a shoe holding stand made in accordance with the invention.

Fig. 2 is a top plan view of the same.

Fig. 3 is an end view, looking from the rear end of the stand.

Fig. 4 is a horizontal longitudinal sectional view above the clamping levers, on the line 4—4 of Fig. 1.

Referring particularly to the accompanying drawings, 10 represents a base which is adapted to be secured to a floor or other suitable location, and carried by the base, and rising centrally therefrom, is a standard 11. On the upper end of the standard is a transverse head 12 of greater width than the standard and constituting a foot rest. In the opposite side edges of one end of the foot rest 12 are formed the regularly spaced notches 13, the purpose of which will presently appear. Depending from each end of the foot rest is a loop 14, in the inner vertical edge of one leg of each of which is formed a longitudinal series of notches 15.

In the standard 11, is formed a longitudinal series of openings 16, and engaged around the standard is a collar through which, and through any one of said openings 16 is arranged to be passed a pin 18 for holding said collar 17 at different heights. The collar 17 is formed with oppositely extending pairs of ears 19, which are directed toward the before-mentioned loops 14. Pivottally mounted between each pair of ears 19 is the inner end of a lever 20, the outer end being disposed between the legs of a loop 14, and arranged to be engaged in the notches 15 of said loops. Each lever 20 is formed with a longitudinal series of openings in any one of which is arranged to be engaged a bolt 21, on which bolt is carried a vertically extending link 22. The upper end of each link 22 is twisted to lie in a plane at right angles to the lever, and pivotally connected to said upper portion of each link is a pair of upwardly diverging hook arms 23, said arms being arranged to engage their hook ends with the edges of the sole of a shoe placed on the foot rest, as clearly seen in Figs. 1 and 3, of the drawings.

The standard 11 is suitably braced with respect to the base, by the inclined braces 24.

The shoe is placed on the foot rest with the heel slightly in rear of the notches 13, so that the narrow portion of the sole of the shoe, in advance of the heel thereof, is directly over the adjacent arms 23, and the forward or toe portion of the shoe over the forward arms 23. The rear arms 23 are then engaged with the opposite edges of the sole, in advance of the heel, and the lever 20 pressed down and engaged in one of the notches 15, to firmly clamp the heel portion of the shoe to the rest. The front arms 23 are then engaged with the edges of the forward portion of the shoe sole and the lever 20, thereof, drawn down and engaged with the proper notch 15, of the front loop 14, whereby the shoe is firmly held on the stand, so that the operation of polishing can be performed on the shoe without danger of the shoe moving. The operator thus can use both hands in the polishing operation, and will not need to hold the shoe with one hand and perform the polishing operation with the other hand, as is the case with the ordinary shoe stand, or method employed.

For shorter shoes the arms 23 are moved inwardly toward the standard, and for

larger shoes they are moved away from the standard. By adjusting the collar 17 vertically on the standard, the grip of the arms 23 can be regulated.

5 The walls of the notches 13 receive the arms 23, at the rear of the device, and serve to prevent the arms from movement forwardly or rearwardly, as will be readily understood.

10 The device is especially useful in hotels, railway sleepers, and for domestic or home use.

What I claim is:

15 A shoe blacking stand comprising a standard having a foot rest on its upper end, a vertically adjustable collar on the standard, levers pivotally carried by the collar and extending toward the ends of the foot rest,

depending loops carried by the ends of the foot rest, one leg of each loop having an inner vertical series of notches for engagement by the levers, and pivotally connected shoe sole gripping arms carried by the levers and diverging upwardly at the sides of the foot rest, said foot rest having notches in the 25 edge portions of one end thereof to receive one set of gripping arms to maintain the gripping arms against movement longitudinally of the foot rest.

In testimony whereof, I affix my signature, 30 in the presence of two witnesses.

JOHN J. BRENTANO.

Witnesses:

BERNARD BRENTANO,
ELIZABETH BRENTANO.
